CLAIM

I claim the ornamental design for a massage device, as shown and described.

DESCRIPTION

FIG. 1 is a perspective view of a massage device, which shows front, left, and top sides;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof; and,

FIG. 7 is a left side elevation view thereof.

The broken lines shown in the figures are for the purpose of illustrating portions of the massage device, which form no part of the claimed design.

1 Claim, 4 Drawing Sheets
